WEATHERING TESTING DEVICE

Robert Davie, Freeport, N. Y.

Application November 19, 1945, Serial No. 629,684

7 Claims. (Cl. 219—38)

(Granted under the act of March 3, 1883, as
amended April 30, 1928; 370 O. G. 757)

1

This invention relates to a weathering testing device.

It is an object of this invention to provide a device wherein an atmosphere of controlled temperature and humidity can be maintained over extended periods of time.

Another object is to provide a device wherein accelerated weathering tests at relatively high temperatures and humidities can be conducted.

Further objects and advantages of this invention, as well as its construction, arrangement and operation, will be apparent from the following description and claims in connection with the accompanying drawing, in which the figure is a sectional view of a device embodying the principles of this invention.

The device comprises an outer housing 11 defining a chamber and constructed of insulating materials of sufficient thickness to prevent appreciable passage of heat therethrough. Substantially centered within outer housing 11 in spaced relation therefrom and concentrically enclosed thereby is an inner housing 12 defining a chamber and made of sheet steel or similar semi-conducting material permitting appreciable heat transfer therethrough by conduction. Shelves 13, of wire screen or similar material not seriously affecting the circulation of air therethrough, are desirably provided within inner housing 12. Both housings 11 and 12 are provided with adjacent access doors (not shown), which can be provided with double-paned glass windows to permit observation of the interior of the inner housing 12 from the exterior of the outer housing 11.

Approximately centered in the lower surface of outer housing 11 is a vent 14, which also serves as a drain. An opening 15 is provided in the lower surface of inner housing 12, preferably directly above vent 14. A plurality of vents 16 are provided in the sides of housings 11 and 12 near the tops thereof. Vents 16 can be provided with adjustable apertures, to regulate the flow of air therethrough.

Heat is supplied to the device in the lower space between outer housing 11 and inner housing 12, as by electrical resistance 17. Resistance 17 is preferably automatically controlled, as by thermostat 18, the location of the automatic control device being above resistance 17 but outside inner housing 12. Water pan 19, which can be kept filled to constant level by means of tube 20, rests upon pad 21, near the bottom of the interior of inner housing 12, and preferably directly above opening 15. Water pan 19 can serve as a constant source of water vapor through the

2

insertion of an immersion heater therein, illustrated as electrical resistance 22, controlled by rheostat 23 located outside outer housing 11. Conventional devices indicating temperature and humidity can be employed in the interior of inner housing 12, and can be connected to indicating and recording devices outside outer housing 11, or can be observed through glass inserts in the access doors or walls of housings 11 and 12.

10 The device functions in the following manner. A plurality of objects which are to be subjected to an extended test at elevated temperatures and humidities are placed upon the shelves 13, and the access doors to housings 11 and 12 closed and locked. Thermostat 18 is then adjusted and current allowed to flow through electrical resistance 17 until the desired temperature is attained in the interior of inner housing 12. This may require readjusting of the thermostat 18 after observing stabilization of the temperature inside inner housing 12. The temperature governing thermostat 18, that is the temperature below inner housing 12, is not the same as the temperature in the interior of inner housing 12, but it has been found that a more constant temperature is maintained in the interior of inner housing 12 by control regulated by the temperature outside the inner housing. Once the interior of inner housing 12 has achieved equilibrium at 20 the desired temperature, thermostat 18 is adjusted to maintain the equilibrium.

After equilibrium at the desired temperature is achieved in the interior of inner housing 12, the desired relative humidity is provided by evaporation of water vapor from water pan 19. The evaporation is caused by the passage of current through electrical resistance 22. The rate of evaporation is controlled by rheostat 23, rheostat 23 being adjusted in accordance with the relative humidity in the interior of inner housing 12 until an equilibrium is achieved at the desired value.

Once adjusted to achieve the desired temperature and relative humidity, the device maintains these conditions with extremely small variations for an indefinite period of time. The location of the heat source, electrical resistance 17, at the bottom of outer housing 11 causes convection through the device, resulting in a steady 30 circulation of air through housings 11 and 12, the air entering through vents 14 and 15 and exiting through vents 16. This circulation of air can be limited by adjusting the openings in vents 16. Once equilibrium has been attained 40 in inner housing 12, the circulation of air through

5 housings 11 and 12 is of considerable value in maintaining the equilibrium, enabling extremely sensitive control of the temperature within housing 12 by thermostat 18. The interior of housing 12 is subjected to much smaller changes of temperatures than is thermostat 18, and is relatively less affected thereby.

10 Constaney of temperature within housing 12, and thereby constancy of relative humidity, is also contributed to by the manner in which heat input to the housing 12 is achieved. Heat can enter inner housing 12 by convection through opening 15, by radiation through opening 15 and to the lower surface of inner housing 12, and by conduction through the walls of inner housing 12. This combination of methods of heat input to the interior of inner housing 12 results in constancy of temperature therein of a high order, easily maintained by thermostat 18 through fluctuations in ambient temperature and other variables. It is desirable that the heat input to the interior of inner housing 12 by conduction through the walls of housing 12 be a considerable proportion of the total input. For this reason the walls of housing 12 are desirably made of material and of a thickness having moderate heat transference properties. Such a semi-conducting material is sheet steel, thicknesses of from $\frac{1}{8}$ " to $\frac{1}{4}$ " having been found especially suitable. Relatively thin walls of material having high heat conducting properties, such as copper, have been found to be unsuitable, causing the proportion of heat input to housing 12 by conduction to be disproportionately large and affecting the constancy of temperature which may be maintained within housing 12. Similarly, the use of materials of high insulating properties in the walls of housing 12, such as asbestos board, results in the proportion of heat input into housing 12 by conduction to be disproportionately small and detrimentally affects the constancy of temperature which may be maintained.

15 It is to be understood that various modifications and changes may be made in this invention without departing from the spirit and scope thereof as set forth in the appended claims.

20 The invention described herein may be manufactured and used by or for the Government of the United States of America for governmental purposes without the payment of any royalties thereon or therefor.

25 What is claimed is:

1. A device for providing an atmosphere of controlled temperature and humidity comprising two concentric, spaced housings, heating means within the space between said housings, and humidifying means within the inner of said housings.

30 2. A device for providing an atmosphere of controlled temperature and humidity comprising two concentric, spaced housings, thermostatically controlled electrical heating means within the space between said housings, and controlled

35 humidifying means within the inner of said housings.

3. A device for providing an atmosphere of controlled temperature and humidity comprising an outer insulating housing, an inner housing of semi-conducting material contained within said outer housing in spaced relation therefrom, thermostatically controlled electrical heating means within the space between said housings, and controlled humidifying means within the inner of said housings.

40 4. A device for providing an atmosphere of controlled temperature and humidity comprising an outer insulating housing, an inner housing of semi-conducting material contained within said outer housing in spaced relation therefrom, said inner housing being open to said outer housing through an opening at its bottom, thermostatically controlled electrical heating means within the space between said housings directly below said inner housings, and controlled humidifying means within said inner housing.

45 5. A device for providing an atmosphere of controlled temperature and humidity comprising an outer insulating housing, an inner housing of semi-conducting material contained within said outer housing in spaced relation therefrom, said inner housing being open to said outer housing through an opening at its bottom, electrical heating means within the space between said housings directly below said inner housing, said heating means being controlled by a thermostat above said heating means but outside said inner housing, and controlled humidifying means within said inner housing.

50 6. A device for providing an atmosphere of controlled temperature and humidity comprising an outer insulating housing, an inner housing of semi-conducting material contained within said outer housing in spaced relation therefrom, said inner housing being open to said outer housing through an opening at its bottom, thermostatically controlled electrical heating means within the space between said housings directly below said inner housing, controlled humidifying means within said inner housing, and a plurality of vents in said housings permitting controlled circulation therethrough.

55 7. A device for providing an atmosphere of controlled temperature and humidity comprising two substantially concentric, spaced housings, heating means within the space between said housings, and humidifying means within said housings.
